UNITED STATES PATENT OFFICE

2,328,661

BREAKING DEVICE

Joseph F. Maloney, University City, Mo.

Application March 10, 1941, Serial No. 382,559

5 Claims. (Cl. 262—12)

This invention relates generally to devices for breaking rock, stone, concrete, and similar structures, and more specifically to devices of this type which rely on expansive action to perform their intended functions, the predominant object of the invention being to provide an extremely simple tool of the type mentioned which is adapted to be introduced into a hole drilled in a structure to be broken with the aid thereof, and which includes laterally movable members arranged to be forced against the wall of the hole by an element having wedge faces, to produce internally initiated, outwardly directed force which effects breaking of the structure being acted upon.

Prior to this invention the explosive action of dynamite was widely used for the purpose of breaking boulders, or large pieces of rock and stone, and large sections of concrete, but due to the fact that dynamite cannot be employed for this purpose under certain circumstances and in certain localities, other means must be employed to perform such breaking operations when the use of dynamite is inadvisable. The main purpose of this invention is to provide such a device for breaking rock, stone, concrete, and the like, which is at once of simple and durable construction and is capable of performing its intended function in a highly efficient manner. An important feature of the invention is that the improved device disclosed herein is capable of being actuated with the aid of a pneumatic hammer, or it may be actuated by blows directed thereagainst with the aid of a sledge or other suitable hand-operated tool.

Fig. 1 is an elevation of the improved device, parts thereof being broken away and the device being shown in place in a hole drilled in a structure to be broken with the device in the position it assumes at the commencement of the breaking operation.

Fig. 2 is an elevation of the device looking toward same from a different angle.

Fig. 3 is a view of the improved device showing same largely in vertical section and partially in elevation.

Fig. 4 is a horizontal section taken on line 4—4 of Fig. 3.

Fig. 5 is a horizontal section taken on line 5—5 of Fig. 3.

Fig. 6 is a horizontal section taken on line 6—6 of Fig. 3.

In the drawing, wherein is shown for the purpose of illustration, merely, one embodiment of the invention, A designates the improved device generally. The device A includes a plug 1 which

is formed of steel or other durable material said plug 1 having a solid head portion 2 at its upper end in which a cavity 3 is formed whose wall is circular when viewed in horizontal section and is provided with heavy screwthreads. Adjacent to the upper end of the plug 1 the head portion 2 thereof has formed thereon an outwardly projected extension 4 which is preferably, though not necessarily, of annular formation.

The plug 1 below the extension 4 is of generally circular shape in cross section, and of substantially constant diameter from said extension to the lower end of the plug, with the exception that said plug is provided with opposed, convergent faces 5 which extend from the points designated by the reference character 6 to points adjacent to the lower end of the plug. The faces 5 are of tapered shape when viewed in elevation as one of said faces is shown in Fig. 2; that is to say, each of said faces 5 is relatively narrow at its upper end and flares outwardly as it extends downwardly to a greater width at its lower end. The opposed faces 5 provide the plug with wedge faces which serve a purpose to be hereinafter set forth. The plug 1 has formed therein a pair of opposed cavities 7 which extend inwardly from the faces 5, said cavities extending downwardly of the plug from the points 6 to points adjacent to the lower end of the plug and the inner wall of each of said cavities being extended in substantial parallelism with respect to the face 5 with which said cavity is associated.

The upper portions of the cavities 7 are shaped as shown in Fig. 4, but disposed downwardly of said upper portions of said cavities the opposed side walls of each thereof are provided with inwardly extended ribs 8 which are projected downwardly from the points 8' to the points adjacent to the lower end of the plug. The front walls of the ribs 8 are substantially flush with the faces 5 and the rear faces of said ribs are spaced outwardly from the inner walls of the cavities 7. Also the inner edge faces of each pair of ribs associated with a cavity 7 are spaced apart to 40 provide a space between said edge faces. The arrangement of the ribs 8 within the cavities 7 give to the portions of the cavities in which the ribs are disposed a T-shaped formation as shown in Figs. 5 and 6. At its extreme lower end the plug 1 is of tapered shape as shown at 9 in Figs. 1, 2, and 3, and the inner portions of the cavities 7 terminate in shoulders 10 which serve as abutments as will be hereinafter explained.

Associated with the plug 1 at its upper end is a stem 11 which is provided with a lower portion

12 that is provided with heavy screwthreads, said stem portion 12 being screwthreadedly disposed within the cavity 3 of the plug. The stem 11 is provided also with an annular flange 13 which contacts with the top face of the plug 1 and thereby serves to prevent downward force resulting from blows to which the stem 11 is subjected in use of the device from being imparted to the screwthreads of the stem portion 12 and the cavity 3.

The device A includes also a pair of slides 14 which are associated in opposed relation with the plug 1 at the faces 5 thereof. The slides 14 are provided with outer faces which are substantially straight in a vertical direction and which are curved horizontally in substantial accordance with the horizontal curvature of the upper portion of the plug 1, said slides having inner inclined faces 15 the inclinations of which are substantially the same as the inclinations of the faces 5 of the plug with which said inner faces of the slides contact. At the upper end of each of the slides 14 a rigid guiding element 16 is formed on said slide, said guiding element extending downwardly from the top face of the slide a short distance as shown to the best advantage in Figs. 1 and 3. The guiding elements 16 of the slides 14 are of substantially T-shaped formation in cross-section as shown in Fig. 5, and said guiding elements extend into the opposed cavities of the plug 1 with the outwardly projected ribs 16' of said guiding elements 16 extending behind the ribs 8 of said cavities when the guiding elements of the slides are located in the portions of the cavities which are rendered T-shaped in cross-section by said ribs 8. Also each of the slides has formed on the inner inclined face thereof a web 17 which is of less height than the associated guiding element and extends downwardly from the lower end of said guiding element a substantial distance, said webs 17 of the slides being extended into the spaces between the inner edge faces of the associated ribs 8 of the plug 1 as shown to the best advantage in Fig. 6.

From the foregoing it is obvious that the slides 14 are guided for movement with respect to the plug 1 with the inclined faces 15 of said slides in sliding contact with the inclined faces 5 of the plug, and because of the interengaging relation of the ribs 16' of the guiding elements of the slides and the ribs 8 of the plug said slides are prevented from becoming detached from the plug by moving outwardly therefrom. Also, the slides 14 may not become detached from the plug 1 by passing from the lower end thereof because of the presence of the shoulders 10 which will engage the lower end of the guiding elements of the slides to arrest downward movement of the slides relative to the plug and thus prevent such detachment of the slides from the plug. Furthermore, when it is desired to remove the slides 14 from the plug for repair, replacement or for any other reason, the slides may be moved upwardly with respect to the plug until the guiding elements of said slides clear the upper ends of the ribs 8 of the plug whereupon the slides may be moved outwardly from the plug to cause the guiding portion of the slides to move through the unribbed upper portions of the cavities 7 (see Fig. 2).

When it is desired to break a boulder of rock or stone, a section of concrete, or other similar structure, a hole is drilled in the structure as shown in the drawing, where S designates the structure to be broken and H designates the hole

drilled therein. The device is then introduced into the hole in the structure S with the slides 14 in a contracted condition at the lower end of the plug 1. The upper end of the stem 11 is then subjected to blows to drive the plug 1 downwardly relative to the slides, the inclined faces 5 of said plug moving downwardly against the inclined inner faces of the slides to spread said slides and force them outwardly against the wall of the hole of the structure being broken to a sufficient degree to crack and break the structure being acted upon. The blows against the upper end of the stem 11 may be delivered by a sledge or other suitable hand-operated tool, or, if desired, a pneumatic hammer may be employed to deliver said blows, the upper end portion of said stem being of such shape and dimensions that the chuck of the pneumatic hammer will rotate with respect to said upper end of the stem without imparting rotary movement thereto.

If, for any reason, the device should become jammed in a portion of the hole of a structure which has been broken with the aid of the device, the flange 4 of the plug 1 may be employed as aid in extracting the device. This may be accomplished by engaging the lower face of the flange 4 with the end portion of a crowbar, under which a rock or other article is arranged to provide a fulcrum, and employing the crowbar as a lever to force the device upwardly out of the hole.

An important feature of the invention resides in the fact that the stem 11 is detachable from the plug 1 of the device, by unscrewing same from the cavity 3, and hence may be removed for repair or replacement when it is bent, broken, or battered because of blows directed thereagainst during use of the device. Also the screwthreads of the stem are preferably left-hand threads so that the rotating chuck of a pneumatic hammer employed to operate the device A will not tend to unscrew said stem from the cavity 3.

I claim:

1. A breaking device comprising a plug provided with opposed wedge faces, elongated cavities formed in said plug at the wedge faces thereof and provided each with opposed webs extending from opposed walls thereof, a pair of slides disposed at opposite sides of said plug and arranged for sliding movement relative to said plug, said slides being provided with inclined faces which contact with the wedge faces of said plug for relative sliding movement between said wedge faces and said inclined faces, guiding elements extended from said slides into said cavities of the plug and having webs which project behind the webs of said cavities for guiding the relative movement of said plug and slides and maintaining said slides in sliding engagement with said plug, and guiding webs formed on said slides and extended from said guiding elements longitudinally of said slides and adapted to move between the webs of said cavities of the plug on relative movement of the slides and plug.

2. A breaking device comprising a plug provided with opposed wedge faces, elongated cavities formed in said plug at the wedge faces thereof and provided each with opposed webs extending from opposed walls thereof, a pair of slides disposed at opposite sides of said plug and arranged for sliding movement relative to said plug, said slides being provided with inclined faces which contact with the wedge faces of said plug for relative sliding movement between said wedge faces and said inclined faces, guiding elements

extended from said slides into said cavities of the plug and having webs which project behind the webs of said cavities for guiding the relative movement of said plug and slides and maintaining said slides in sliding engagement with said plug, and guiding webs formed on said slides and extended from said guiding elements longitudinally of said slides and adapted to move between the webs of said cavities of the plug on relative movement of the slides and plug, said webs of the elongated cavities of the plug terminating at their upper ends at points spaced downwardly from the upper ends of said cavities to provide upper unwebbed cavity portions through which the guiding elements of the slides may be passed to disconnect the slides from the plug.

3. A breaking device comprising a plug provided with opposed wedge faces, elongated cavities formed in said plug at the wedge faces thereof and provided each with opposed webs extending from opposed walls thereof, a pair of slides disposed at opposite sides of said plug and arranged for sliding movement relative to said plug, said slides being provided with inclined faces which contact with the wedge faces of said plug for relative sliding movement between said wedge faces and said inclined faces, guiding elements extended from said slides into said cavities of the plug and having webs which project behind the webs of said cavities for guiding the relative movement of said plug and slides and maintaining said slides in sliding engagement with said plug, guiding webs formed on said slides and extended from said guiding elements longitudinally of said slides and adapted to move between the webs of said cavities of the plug on relative movement of the slides and plug, said webs of the elongated cavities of the plug terminating at their upper ends at points spaced downwardly from the upper ends of said cavities to provide upper unwebbed cavity portions through which the guiding elements of the slides may be passed to disconnect the slides from the plug, and abutments at the lower portion of said plug with which the guiding elements of the slides contact to limit relative movement of the slides and the plug.

4. A breaking device comprising a plug provided with opposed wedge faces, elongated cavities formed in said plug at the wedge faces thereof and provided each with opposed webs extend-

ing from opposed walls thereof, a pair of slides disposed at opposite sides of said plug and arranged for sliding movement relative to said plug, said slides being provided with inclined faces which contact with the wedge faces of said plug for relative sliding movement between said wedge faces and said inclined faces, guiding elements extended from said slides into said cavities of the plug and having webs which project behind the webs of said cavities for guiding the relative movement of said plug and slides and maintaining said slides in sliding engagement with said plug, and an extension formed at the upper portion of said plug which serves to aid in removing the device from a hole in which it may be disposed.

5. A breaking device comprising a plug provided with opposed wedge faces, elongated cavities formed in said plug at the wedge faces thereof which are each undercut at their opposite sides so as to provide said cavities with inner portions that are of greater width than the outer slot-like portions of the cavities which are open at the wedge faces of the plug, a pair of slides disposed at opposite sides of said plug and arranged for sliding movement relative to said plug, said slides being provided with inclined faces which contact with the wedge faces of said plug for relative sliding movement between said wedge faces and said inclined faces, guiding elements extended from said slides into said cavities of the plug and having relatively wide inner portions which extend into the undercut inner portions of said cavities and slide longitudinally thereof, and narrower outer portions which are disposed in the outer slot-like portions of said cavities and slide longitudinally thereof for guiding the relative movement of said plug and slides and maintaining said slides in sliding engagement with said plug, the slot-like outer portions of said cavities terminating at their upper ends in openings which are of approximately the same width as the widest portions of the inner undercut portions of the cavities and which are at least of slightly greater height than said guiding elements to allow for passage of said guiding elements through said openings and thereby permit detachment of the slides from the plug, and means for limiting relative movement of the slides and the plug.

JOSEPH F. MALONEY.
